UNITED STATES PATENT OFFICE.

JOHN HENRY MEYERS, OF GRAND ISLAND, NEBRASKA.

DENTAL INSTRUMENT.

1,197,648.

Specification of Letters Patent. Patented Sept. 12, 1916.

Application filed May 15, 1916. Serial No. 97,644.

To all whom it may concern:

Be it known that I, JOHN HENRY MEYERS, a citizen of the United States, residing at Grand Island, in the county of Hall and State of Nebraska, have invented certain new and useful Improvements in Dental Instruments; and I do declare the following to be a full, clear, and exact description of the invention, such as will enable others skilled in the art to which it appertains to make and use the same.

This invention relates to improvements in dental instruments and more particularly to tools for holding crowns and the like while being ground or polished.

The object of the invention is to provide an instrument of this character which is simple in construction and which while easily engaged with a crown, will securely hold it against turning during the polishing or grinding thereof.

With the above and other objects in view, the invention resides in certain novel features of construction, and the combination and arrangement of parts as will be herein-after more particularly described and claimed.

In the accompanying drawings: Figure 1 is a side elevation of an instrument constructed in accordance with this invention with the jaws in closed position; Fig. 2 is a longitudinal section thereof; Fig. 3 is a similar view taken in a plane at right angles to Fig. 2 on the line 3—3 of Fig. 2, and 35 with the jaws in open position; Fig. 4 is a transverse section taken on the line 4—4 of Fig. 3; Fig. 5 is a similar view taken on the line 5—5 of Fig. 3; and Fig. 6 is a detail perspective view of one of the jaws.

In the embodiment illustrated, a handle 1 is shown having a socket 2 with oppositely disposed grooves 3 therein to receive lateral retaining projections 4 on a head 5, said projections being here shown in the form of rectangular screw heads which are designed for securing longitudinally extending plate springs 6 and 7 to said head. These square heads when inserted in the grooves 3 serve to hold the head against turning relatively to the handle. This head

5 is shown provided with oppositely disposed openings 8 in its side walls in which said springs 6 and 7 are mounted, one end being secured to the head adjacent the inner end of the opening and the other end extending forwardly into the head, said forwardly projecting end of each spring being shown reduced and the spring curved longitudinally outward to adapt the free ends thereof to bear forcibly against the inner ends of tool engaging jaws 10 and 11 presently to be described.

Two parallel longitudinally extending laterally spaced arms 12 and 13 project from the front end of the head and have an opening between them which communicates with the interior of the head and through which extends the free ends of the springs 6 and 7.

Pivoted between the arms 12 and 13 at the front ends thereof are the two jaws 10 and 11 which are exactly alike in formation, the opposed faces of which are rectilinear throughout the greater portion of their length and are designed when the jaws are in closed position to contact. The pivots 9 which connect the jaws and the arms 12 and 13, extend through said jaws at points spaced inwardly from their rear ends, said rear ends being of a length slightly less than the distance between the pivots 9 and 5 from which the arms extend so as to provide ample space to permit the jaws to swing laterally between said arms. One of these jaws is shown in detail in Fig. 6 and the inner face or edge thereof is cut 85 away from a point slightly in advance of the fulcrum receiving opening 9' therein to the rear terminal of the jaw. A shoulder 14 is formed at the front end of said cut-away portion, the front corner of which is 90 beveled for a purpose to be described. The cut-away portion of the jaw is also inclined inwardly toward its free rear end and against which face the outwardly bent terminal of one of the springs is designed to 95 engage so that when the jaws are assembled and pivotally mounted between the arms 12 and 13 of the head 5, the inner faces of their rear terminals will be spaced some distance apart to provide for their move- 100

ment toward each other on the separation of the front ends of the jaws by means to be described.

The free front ends of the jaws 10 and 11 are shown serrated or toothed on their outer faces to provide gripping means for engaging and securely holding the crown or other article with which the jaws are adapted to be engaged, it being understood that the closed ends of the jaws are inserted in the crown and then forced open for holding it securely in engagement with said crown.

The means for opening the jaws is shown in the form of a rod 15 having a milled operating head 16 at one end and a wedge-shaped member 17 at its other end. This wedge-shaped member is here shown in the form of a cone and is designed to extend between the jaws 10 and 11 for forcing the free ends thereof into open position. This rod 15 is of a length sufficient to extend through the handle 1 and through the hollow head 5 and to project between the rear ends of the jaws pivoted in the arms 12 and 13 of said head. A portion of this rod 15 is threaded for engagement with a threaded extension 5' formed on the rear end of the head 5 and when the parts are in assembled operative position, as shown in Fig. 3, the cone-shaped wedge member 17 will be disposed between the opposed faces of the rear ends of the jaws 10 and 11 with the point of said member extending between the inclined or beveled corners of the shoulder 14 so that when said rod is moved forwardly, its end will be forced between the jaws in advance of their pivots and thereby force the front ends of said jaws open against the tension of the springs 6 and 7 which are engaged with their rear ends as will be clearly seen from Fig. 3. When it is desired to disengage the tool from a crown, the rod is moved rearwardly by turning the same in the opposite direction, thereby disengaging the wedge-like end 17 thereof from the jaws which will immediately close under the action of the springs 6 and 7.

A ferrule 18 is shown arranged around the head 5 in advance of the handle 1 to assist in connecting these parts and to protect the head against the entrance of dust or grit therein.

From the above description, it will be obvious that a neat and compact tool is formed, the parts of which may be readily assembled or disassembled for repairing or other purposes and that to engage or disengage the tool from the object which it is designed to hold, all that is necessary is to turn the milled head 16 in one direction or the other for opening or closing the jaws.

By forming the beveled opposed corners or faces of the jaws in advance of their fulcrums or pivotal points and employing in

connection therewith the cone-shaped opening member 17, these jaws may be gradually opened to bring their biting ends into engagement with a crown so that while it will be reliably held, all danger of injuring it or changing its configuration, will be avoided. 70

I claim as my invention:

1. A device of the class described comprising a pair of pivotally mounted jaws, resilient means engaging said jaws on one side of their pivot for moving them into 75 closed position, and a jaw opening member operable between them on the side of the pivot opposite to the side with which the closing means is engaged, whereby the jaws are forced apart against the tension of their 80 closing means.

2. A device of the class described comprising a head, a pair of jaws pivotally mounted therein intermediate of their ends, resilient means for holding said jaws in 85 closed position, and a wedge-shaped member movable longitudinally between the jaws from the rear end thereof for engagement with their opposed faces in advance of their pivotal connection for opening the jaws 90 against the tension of their resilient closing means.

3. A device of the class described comprising a head, a pair of jaws pivotally mounted therein intermediate of their ends, resilient 95 means for holding said jaws in closed position, and a wedge-shaped member movable longitudinally between the jaws from the rear end thereof for engagement with their opposed faces in advance of their pivotal connection for opening the jaws against the tension of their resilient closing means, the opposed faces of said jaws in advance of their pivotal connection converging forwardly to receive said wedge-shaped opening member and by means of which the jaws may be gradually opened on the forward movement of said member. 105

4. A device of the class described comprising a hollow head having forwardly extending laterally spaced parallel arms at its front end and an internally threaded extension at its rear end, jaws pivotally mounted intermediately of their ends between said arms, springs carried by said head and mounted between the rear ends of said arms for forcing them apart and their front ends into closed position, and a rod having threaded engagement with the extension at the rear end of said head and provided with a wedge-like member for insertion between said jaws in advance of their pivotal connection whereby their front ends are forcibly separated against the tension of their springs. 120

5. In a device of the class described, a handle having a bore extending longitudinally therethrough and enlarged at its front 125

end to form a socket, said socket having oppositely disposed grooves in its side walls, a hollow head having a tubular extension at its rear end for insertion in said socket, pivoted jaws carried by said head, springs normally closing said jaws, attaching screws for said springs having angular heads for engagement with the grooves of said handle socket whereby said head is held against turning relatively to said handle, a jaw

opening member movable longitudinally in said handle and head, and actuating means for said member.

In testimony whereof I have hereunto set my hand in presence of two subscribing witnesses.

JOHN HENRY MEYERS.
